UNITED STATES PATENT OFFICE

THOMAS E. WYKES, JR., OF GRAND RAPIDS, MICHIGAN

CARD HOLDER

Application filed May 31, 1927. Serial No. 195,218.

This invention relates to a card holder which is particularly useful in conjunction with giving information respecting the lubrication of motor vehicles, and as one feature 5 of the invention a simple and convenient means is utilized for releasably holding the card holder on the instrument board of the automobile adjacent the speedometer whereby, upon the speedometer readings showing 10 the attainment of certain mileages noted on the cards held in the card holder instructing that certain parts of the automobile should be lubricated, such lubrication will be attended to. The card holder itself may be 15 used in other relations but is particularly effective in the relation stated.

An understanding of the invention may be had from the following description taken in connection with the accompanying drawing, 20 in which,

Fig. 1 is a fragmentary perspective view of the instrument board of an automobile illustrating the card holder mounted thereon adjacent the speedometer.

Fig. 2 is a fragmentary enlarged front elevation of the instrument board showing the card holder mounted thereon.

Fig. 3 is a vertical section through the construction shown in Fig. 2, and

Fig. 4 is a perspective view of the card holder.

Like reference characters refer to like parts in the different figures of the drawing.

The instrument board 1 of automobiles is 35 now made almost universally of metal and with my invention a pocket is made therein by pressing the metal inward so as to provide a back 2 and upper and lower sides 3 and 4, the upper side being inclined upwardly 40 and inwardly and the lower side downwardly and inwardly as shown. Midway between the ends of the lower side 4 a recess 5 is made of a shape to readily receive a finger of the operator of the car in removing the card holder which is to be held in said pocket.

The card holder is made of rubber or like 45 flexible and elastic material and has a thin back 6, two spaced apart vertical sides 7, a lower side 8 and an upper side 9. The sides 50 7 and 8 are grooved at their inner sides while

the upper side 9 is made slotted nearly its entire length as indicated at 10, so that a plurality of cards may be slidably received in the grooves of the vertical and lower sides 7 and 8 through the slot 10. A recess 11 is 55 cut in the upper edge of the back 6 in order that the cards may be engaged by the finger for removal or replacement. Also a flexible transparent closure 12 of celluloid, mica or the like may be placed in the card holder to 60 lie in front of the cards which are indicated at 13.

A card holder of the type described being flexible and elastic may be readily sprung or bent so that its upper and lower ends can be 65 placed between the inclined upper and lower sides 3 and 4 of the pocket and, when released, will spring back and engage against the inclined ends of the pocket and be held frictionally therein. By inserting a finger in 70 the recess 5 the card holder may be removed at any time by flexing it sufficient to disengage at its inner end from its lower inclined side 4 of the pocket.

The cards 13 carry instructions as to what 75 parts of the automobile should be lubricated after the same has been driven a certain mileage and it will be noted that the card holder is located on the instrument board in close proximity to the speedometer 14 from 80 which information as to the mileage of the car is obtained. A series of cards are required to cover the full mileage that an automobile should run before it is worn out. The cards may be rearranged in the holder whenever necessary to bring the proper card corresponding to the mileage shown by the speedometer at the front of the holder.

The constructions described are simple but 85 very useful for the purposes for which designed. The card holder itself is readily manufactured at low cost and the pocket for holding the same may be easily pressed in the instrument board of the automobile. Of course, if the instrument board is of wood the 90 pocket is cut therein rather than pressed as can be done with sheet metal. Variations in detail of construction may be resorted to without departing from the invention which 95 is defined in the appended claims, and, ac- 100

cordingly, the invention is to be considered comprehensive of all forms of structure coming within the scope of the claims.

I claim:

- 5 1. In combination with a vertically positioned supporting board having a pocket formed therein, the upper and lower ends thereof being inclined upwardly and inwardly and downwardly and inwardly respectively, and a card holding receptacle of flexible material located in said pocket and bearing frictionally at its upper and lower ends against the upper and lower sides of the pocket, said card holding receptacle being open at its outer side.
- 10 2. In combination with a rigid member having a depression, a card holding receptacle of flexible material inserted and frictionally held in said depression by engagement of its edges with the sides of said depression, said receptacle having an open outer side and a slotted upper side through which cards may be placed in said receptacle, said slotted upper side being covered by a side of the depression when the receptacle is inserted therein.

In testimony whereof I affix my signature.
THOMAS E. WYKES, JR.
